UNITED STATES PATENT OFFICE

2,174,256

BEVERAGE MIXER

Henry J. Chilton, Chicago, Ill., assignor to The
Liquid Carbonic Corporation, Chicago, Ill.

Application August 10, 1936, Serial No. 95,114

2 Claims. (Cl. 259—54)

My invention relates to improvements in machines for agitating bottles containing liquids, for the purpose of thoroughly mixing the contents of the bottles.

5 It is primarily intended for use in agitating bottled beverages so that the syrup and the carbonated water contained in the bottle, after the bottle has been filled and sealed, may be thoroughly mixed together.

10 My invention has for one of its objects that of mechanically oscillating the bottle on an axis substantially at right angle to the axis of the bottle during its conveyed movement, so that the position of the bottle will be alternately reversed

15 to cause the liquid contained in the bottle to flow back and forth therein.

For the purpose of disclosing my invention, I have illustrated an embodiment thereof in the accompanying drawings, in which:

20 Fig. 1 is a plan view of a machine embodying my invention;

Fig. 2 is a longitudinal sectional view thereof;

Fig. 3 is a developed plan of the agitating cam; and

25 Fig. 4 is a longitudinal section of one of the bottle clamping members.

In the embodiment of the invention illustrated, a table or platform 1 is mounted on suitable supporting legs 2. This platform has extending upwardly therefrom a central supporting stud 3 on which is adapted to revolve a rotating table 4. This rotating table is driven through the medium of a ring gear 5 mounted on the underside of the rotating table and meshing with the driving pinion 6 mounted on the upper end of the vertical shaft 7 journalled in a vertical bearing 8 and having a driving connection with a worm gear 9 supported on platform 10 carried by the legs 2 beneath the table 1. This worm gear is provided

30 with a horizontal shaft 11 having a driving pulley 12 mounted thereon and provided with a belt drive connection 13 with a driving motor 14. A suitable clutch mechanism is provided in the worm gear by which the worm gear may be

35 connected or disconnected with the shaft 11.

A plurality of radially extending ribs 15 are formed on the upper surface of the turntable 4 and these ribs at their outer ends extend upwardly and outwardly to provide supporting arms 15'. 50 These supporting arms 15' are arranged in pairs and between each pair of arms is pivotally mounted a bottle support. This bottle support comprises a supporting platform 16 having sidewalls 17 and extending outwardly from an oscillating tubular member 18. The upper end of this tubu-

lar member is provided with a crossbar 19 pivotally supported between a pair of the arms 15'. This tubular stem or member 18 is also provided with a rearwardly and angularly disposed arm 19' carrying a roller 20, the purpose of which will more fully hereinafter appear. Means are provided for clamping the bottle on the support 16 and this means comprises a vertically movable rod 21 having a clamping arm 22 adjustably mounted at the top of the rod and adapted to project over the platform 16. This rod is biased in its clamping position by means of a coiled spring 23 enclosed within the tubular stem 18 and surrounding the rod 21. The upper end of this spring bears against the top of the stem 18 and the lower end bears against a collar 24 mounted on the lower end of the rod 21. The spring, therefore, places sufficient pressure on the rod 21 to clamp the end of the arm 22 upon the top of a bottle after the bottle has been placed in position upon the support 16.

The bottles being placed upon the support 16 are adapted to be oscillated with the support as the support rotates with the table 4. To this end, I provide on the supporting table 1 an operating cam track comprising the two spaced apart track members 25 and 26 stationarily mounted on supporting pillars or standards 27 at spaced intervals around the cam track and extending upwardly from the base or table 1. 30 This cam track has a peculiar configuration, as illustrated in Fig. 3. It has a substantially straight portion 28 at the receiving point of the apparatus. This substantially straight portion, which is so disposed as to maintain the platform 35 16 in a horizontal and receiving position, then bends outwardly and upwardly as at 29 to cause the arm 19' and its associated roller 20 to rock the support 18 on its pivot until the bottle is substantially inverted, as illustrated at the right 40 of Fig. 2. The cam then bends downwardly and inwardly as at 30 to reverse the movement of the support to move the bottle back to almost vertical position. This waving shape of the cam may be repeated as many times as is desirable, in 45 the present instance there being four more additional waves during a complete cycle of a bottle, so that the bottle is repeatedly oscillated from the vertical or near vertical inverted position during the rotation of the table 4. By the time 50 the bottle has reached its delivery position again, the roller 20 will have been moved into the portion 28 of the track to cause the platform to resume its position with the bottle vertical. During the movement of the roller 20 in the portion 55

- 28 of the cam track, the clamping arm 22 is raised sufficiently to permit a bottle to be inserted beneath or removed from beneath the same. This is accomplished by means of a roller 5 31 at the bottom end of each of the rods 21, which roller engages an elevating cam 32 mounted on the table 1 beneath the vertically moving rod 21. As the roller 31 passes over this cam, the rod will be raised sufficiently to move the arm 10 22 out of clamping position.
- 15 The bottles are delivered to and received from the agitating mixing device by means of a traveling conveyor 33 arranged at one side of the mixer and tangentially to the periphery of the table 1. At the delivery point, one of the guides 20 34 at the side of the conveyor 33 is provided with an inwardly curved portion 35 against which the bottle impinges and by which the bottle is guided on to one of the platforms 16, it being remembered that the table rotates in the direction of the arrow as indicated in Fig. 1. A similar pick-off guide 36 is placed at the delivery point in the rotation of the table against which the bottle on the platform 16 will strike and be 25 guided off of the platform on to the traveling conveyor. As above explained, at the charging

and discharging point, the clamping arm 22 is raised to permit the bottle to be inserted therebeneath.

I claim as my invention:

1. A machine of the character described, the combination with a rotary table, of a bottle support pivoted on said table and rotatable therewith, an irregular circular cam stationarily mounted relatively to said table and above the plane of said table, having a portion maintaining said support in a horizontal position for a portion of its travel and a portion for imparting an oscillating movement to said support and a roller operatively connected with said support and engaging said cam. 10

15 2. In a machine of the character described, the combination with a rotary table, of a bottle holder pivotally mounted on said table and rotatable therewith and adapted to receive the bottle in a vertical upright position, a circular cam associated with said table and relatively stationarily mounted above the plane of said head, a roller on said holder engaging said cam, the contour of said cam being such as to impart a series of oscillations to said holder. 20

25 HENRY J. CHILTON.

CERTIFICATE OF CORRECTION.

Patent No. 2,174,256.

September 26, 1939.

HENRY J. CHILTON.

It is hereby certified that error appears in the printed specification of the above numbered patent requiring correction as follows: Page 2, second column, line 22, claim 2, for the word "head" read table; and that the said Letters Patent should be read with this correction therein that the same may conform to the record of the case in the Patent Office.

Signed and sealed this 31st day of October, A. D. 1939.

(Seal)

Henry Van Arsdale,
Acting Commissioner of Patents.
